UNITED STATES PATENT OFFICE

MICHAEL M. VARADY, OF CLEVELAND, OHIO

DESIGN FOR A WRINKLE IRON

Application filed October 3, 1931. Serial No. 41,299. Term of patent 14 years.

To all whom it may concern:

Be it known that I, MICHAEL M. VARADY, a citizen of the United States, residing at Cleveland, in the county of Cuyahoga and State of Ohio, have invented a new, original, and ornamental Design for a Wrinkle Iron, of which the following is a specification, reference being had to the accompanying drawings, forming a part thereof.

Fig. 1 of the drawings is a plan of a wrinkle iron showing my new design; Fig. 2 is a side elevation of the same, and Fig. 3 is an end view looking from the left of Figs. 1 and 2.

I claim:

The ornamental design for a wrinkle iron, substantially as shown.

MICHAEL M. VARADY.
